The Adlake Company, Chicago, Ill., a corpora-
tion of Illinois

Application September 15, 1945, Serial No. 616,639

5 Claims. (Cl. 20—56.5)

1

This invention has to do with double glass sash of the type commonly used in the windows of air conditioned railway cars, busses, airplanes, and the like.

In sash of this type the temperature at one side of the sash is frequently much higher or lower than the temperature at the other side. The dead air space which is present between the panes serves to insulate the sash throughout the area of such space but in those double glass constructions which have heretofore been proposed, the conductive character of the surrounding rails, even when the rails have been made in laterally separated sections, has in large measure offset the advantages derived by such insulation, due primarily to the lack of insulation at the points of connection between the sections.

The object of the present invention is to provide an improved double glass sash in which the rails of the sash consist of two laterally separated frame members which are connected together in laterally spaced relation by the employment of novelly constructed and arranged fastening means.

While the invention is especially applicable to double glass sash, certain features of the same can also be utilized advantageously with sash having a single pane or any number of panes, and with doors, panels, and the like, as well as sash.

Several different embodiments of the invention are presented herein by way of exemplification, but it will of course be understood that the invention is susceptible of incorporation in various other structurally modified forms coming equally within the scope of the appended claims.

In the accompanying drawings:

Fig. 1 is a face view of a double glass sash constructed in accordance with the invention;

Fig. 2 is a perspective sectional view through one of the rails of the sash, taken on the line 2—2 of Fig. 1;

Fig. 3 is a transverse section, taken on the line 3—3 of Fig. 1;

Fig. 4 is a perspective view of one of the non-metallic clamping blocks used in securing together the laterally separated sections of the rails;

Fig. 5 is a face view of a somewhat similar double glass sash constructed in accordance with the invention, showing the employment of modified clamping blocks, which blocks also bridge the joints in the rails;

Fig. 6 is a perspective sectional view through one of the rails at the location of one of the

joints, showing the clamping block before application to the joint;

Fig. 7 is a transverse section at the location of the block, taken on the line 7—7 of Fig. 5;

Fig. 8 is another transverse section at the location of the block, taken on the line 8—8 of Fig. 5;

Fig. 9 is an inner face view of the bridging block;

Fig. 10 is a side view of the same block;

Fig. 11 is a perspective sectional view through one of the rails of a sash, showing a slightly modified form of the invention;

Fig. 12 is a transverse section through the rail

shown in Fig. 11; and

Fig. 13 is a perspective view of the clamping block shown in Figs. 11 and 12.

The embodiment of the invention which is shown in Figs. 1 to 4, inclusive, will first be de-

scribed. As will be observed in these views, the frame of the sash consists of two generally rectangular sections or rim members 10 and 11 which are spaced apart and extend continuously about the edge of the sash. This frame contains two panels or panes 12 and 13 of glass and a glazing strip 14 of rubber having grooves 15 and 16 in which the edges of the panes are tightly clamped. The glazing strip 14 is in turn tightly clamped between two inwardly extending flanges 17 and 18 on the rim members 10 and 11.

The rim members 10 and 11 are provided, in addition to the flanges 17 and 18, with outwardly extending flanges 19 and 20, laterally extending

webs 21 and 22, and short outwardly extending flanges 23 and 24 at the confronting edges of the webs 21 and 22. The flanges 23 and 24 are spaced apart in generally parallel relation to each other adjacent the medium plane of the

sash. The flanges 19 and 20 and the webs 21 and 22 together form an outwardly opening channel for the reception of the hereinafter described connecting means.

The connecting means consists of a plurality of E-shaped clamping blocks 25 which are provided with base portions 26, inwardly extending side projections 27 and 28, an inwardly projecting center projection 29, and inwardly extending grooves 30 and 31 between the side

and center projections. These blocks are preferably formed from some strong, tough non-conductive material, such as a phenolic compound, and are made sufficiently hard and rigid to withstand the clamping stresses to which they are subjected.

The blocks 25 are located at intervals about the edge of the sash, within the contour of the frame, with the side projections 27 and 28 of the blocks arranged in clamped abutment with the oppositely facing seats 32 and 33 presented by the short outwardly extending flanges 23 and 24, and with the center projection 29 disposed between the flanges 23 and 24. The blocks are applied to the sash after the panes 12 and 13 have been inserted in the grooves 15 and 16 of the glazing strip 14 and after the glazing strip has been placed between the rim members 10 and 11. The rim members 10 and 11 are forced together under pressure by any suitable means, until the glazing strip 14 has been compressed to the desired degree, whereupon the blocks 25 are inserted in their clamping positions. The blocks will thereupon hold the rim members securely in position, in tightly clamped but properly spaced relation to each other. The ends of the side projections 27 and 28 are preferably beveled at 34 to facilitate their insertions. The blocks will be frictionally retained in place by the expansive action of the glazing strip 14, but if desired may be positively secured in position by means of small non-metallic and preferably resilient cleats 35 which are pivoted at 36 to the backs of the blocks and are movable into positions in which their ends engage within shallow grooves 37 in the edges of the flanges 23 and 24.

In the modified embodiment shown in Figs. 5 to 10 inclusive the spaced rim members 38 and 39 of the frame are clamped together at intervals about the edge of the sash by blocks 40 which are similar to the previously described blocks 25, but in this embodiment each of the rim members, instead of being of continuous one-piece construction, is jointed at 41 and 42, with the joints of one of the rim members staggered with respect to the joints in the other rim member. At the locations of these joints special clamping blocks 43 of greater length than the blocks 40 are employed. The blocks 43 bridge the joints in each rim member, and the relatively short flange 44 of the rim member is cut away at each side of the joint at 45 and 46. The groove 47 in the block which receives the flange 44 terminates short of the ends of the block at 48 and 49, and the resulting solid portions 50 and 51 at the ends of the block extend into the cutout portions 45 and 46 of the flange 44 to lock endwise with the latter and prevent the joint in the rim member from opening up.

In the modified embodiment shown in Figs. 11 to 13 inclusive the clamping blocks 52 are U-shaped in form. In this embodiment the spacing portions of the blocks between the short flanges 53 and 54 of the rim members have been omitted. As in the other embodiments, the rim members are definitely spaced from each other by engagement of the sides of the blocks with the rim members at 55. The blocks 52 may be provided, if desired, with small indexing beads 56 which snap into shallow grooves 57 in the confronting sides of the rim members.

I claim:

1. In a double glass sash, two spaced panes of glass, a rubber glazing strip in which the edges of the panes are clamped, a frame surrounding the panes and comprising two laterally spaced rim members, said rim members being provided with inwardly extending flanges between which the glazing strip is clamped, said rim members being also provided with outwardly extending

flanges in substantially the planes of said inwardly extending flanges, laterally extending webs at the bases of said inwardly and outwardly extending flanges, and other relatively short outwardly extending flanges on the webs adjacent the median plane of the sash, said last mentioned flanges having oppositely facing surfaces, and a plurality of U-shaped connecting members positioned within the contour of the frame in clamped association with the oppositely facing surfaces of the relatively short outwardly extending flanges.

2. In a double glass sash, two spaced panes of glass, a rubber glazing strip in which the edges 15 of the panes are clamped, a frame surrounding the panes and comprising two laterally spaced rim members, said rim members being provided with inwardly extending flanges between which the glazing strip is clamped, said rim members 20 being also provided with outwardly extending flanges in substantially the planes of said inwardly extending flanges, laterally extending webs at the bases of said inwardly and outwardly extending flanges, and other relatively short outwardly extending flanges on the webs adjacent the median plane of the sash, said last mentioned flanges having oppositely facing surfaces and a plurality of U-shaped connecting members positioned within the contour of the frame having 25 clamping portions in clamped association with the oppositely facing surfaces of the relatively short outwardly extending flanges, said connecting members being provided intermediate their clamping portions with spacing 30 projections which extend between the said relatively short outwardly extending flanges.

3. In a sash, one or more glass panes, rubber glazing means for the same, a metal frame in which the glazing means is mounted, said frame 40 consisting of two laterally separable complementary rim sections, each of which is characterized by a facing flange which extends inwardly against one side of said glazing means, a web which extends laterally from the base of said facing flange toward the median plane of the sash, a facing flange which extends outwardly from said web, and a locking flange which also extends outwardly from said web in laterally spaced relation to said outwardly extending facing flange, and one or more removable members positioned between said outwardly extending facing flanges in clamped engagement with said locking flanges for holding said rim sections with the inwardly extending facing flanges thereof in 55 clamped engagement with the sides of said glazing means.

4. In a sash, one or more glass panes, rubber glazing means for the same, a metal frame in which the glazing means is mounted, said frame 60 consisting of two laterally separable complementary rim sections, each of which is characterized by a facing flange which extends inwardly against one side of said glazing means, a web which extends laterally from the base of 65 said facing flange toward the median plane of the sash, a facing flange which extends outwardly from said web, and a locking flange which also extends outwardly from said web in laterally spaced relation to said outwardly extending facing flange, and one or more removable members positioned between said outwardly extending facing flanges in clamped engagement with said locking flanges for holding said rim sections with the inwardly extending facing flanges thereof in 70 clamped engagement with the sides of said glaz-

ing means, said holding means also engaging said outwardly extending facing flanges to space the same.

5. In a sash, one or more glass panes, rubber glazing means for the same, a metal frame in which the glazing means is mounted, said frame consisting of two laterally separable complementary rim sections, each of which is characterized by a facing flange which extends inwardly against one side of said glazing means, a web which extends laterally from the base of said facing flange toward the median plane of the sash, a facing flange which extends outwardly from said web, and a locking flange which also extends outwardly from said web in laterally spaced relation to said outwardly extending facing flange, and one or more removable members positioned between said outwardly extending facing flanges in clamped engagement with said locking flanges for holding said rim sections with

10

15

20

the inwardly extending facing flanges thereof in clamped engagement with the sides of said glazing means, said holding means also engaging said outwardly extending facing flanges to space the same and extending between said locking flanges to space the latter.
